UNITED STATES PATENT OFFICE.

ELMER M. BEARD AND GEORGE A. BEARD, OF BALTIMORE, MARYLAND.

PASSENGER-REGISTER FOR STREET-CARS.

No. 884,557.

Specification of Letters Patent.

Patented April 14, 1908.

Application filed April 13, 1907. Serial No. 367,935.

To all whom it may concern:

Be it known that ELMER M. BEARD and GEORGE A. BEARD, citizens of the United States of America, and residents of Baltimore city, and State of Maryland, have invented certain new and useful Improvements in Passenger-Registers for Street-Cars, of which the following is a specification.

Our invention relates to a device for registering positively all of the passengers who enter a street car. This is accomplished by locating at the entrance a gate which will register each person who passes in. No person can pass out by the same entrance. Heretofore turnstiles of various characters have been employed for the same general purpose, but they have all failed to accomplish a commercial and practical result because of the fact that they occupied too much space upon the platform and required too much space for the sweep of the arms. If they were placed on the platform the arms would project over a large area of platform which could otherwise be occupied by passengers. Our invention is designed to overcome this difficulty and to provide a device which will occupy a minimum of space, which will stand upon the edge of the platform and automatically register each passenger who enters, and close the gate behind the passenger so as to prevent a second passenger from coming through the same opening until the gate has recoiled and made its register.

In the drawings, Figure 1 is an elevation of the rear end of a street car showing the device in position on the platform. Fig. 2 is a plan view in enlarged size of the gate in position on the edge of the platform. Fig. 3 is a side elevation of one of the posts of the gate showing the connection of the arms, the register in position, and the connections below the platform. Fig. 4 is a vertical elevation of one side of the device showing the connection of the moving parts to the register.

Referring to the drawings,—1—1 are a pair of posts located upon the platform of the car upon which are mounted the gate arms 2—2 and 3—3 secured to a sleeve 4; 5 is a rock shaft which passes up through the center of the post 1 into the sleeve 4, where it is secured. It projects through the platform, and to its lower end is secured a segment of a gear 6; a similar segment is secured to the opposite post, and these segments intermesh so as to cause both sides of the gate to move in unison.

7 is a coiled spring, one end of which is secured to a stationary part of the car, and the other end to the segment 6, by which the gates are caused to recoil when a passenger enters the car into the position shown in Fig. 2.

8 is a dash pot secured to the under side of the car by a pivot stud 9.

10 is a piston rod connected to the piston 11 within the dash pot and which at its forward end is connected to the segment 6. By this means the motion of the gates, when recoiling, may be regulated.

12 is the register by means of which the motion of the gates is indicated. It consists of an ordinary intermeshing dial register which will record impulses imparted to it.

13 is a hook located upon the rear of the register, and 14 a pin upon the side of the sleeve 4.

With each motion of the gate in moving forward the pin 14 will move the hook 13 and indicate one upon the register. When recoiling, the pin 14 will pass the pendent hook 13 without making the record.

15 is a lug upon the post 1 which projects up into the path of a lug 16 on the sleeve; these lugs form a stop for the arms and prevent their opening outward. The angle of the two arms of the gate is such that when the inner arms are in a common line, as shown in Fig. 2, the other arms will be sufficiently far apart to enable a passenger to pass between them and take hold of or come into contact with the inner arms. These arms will yield to pressure and the passenger may pass through. The outer arms will immediately follow the passenger and close the opening behind the passenger so as to prevent the admission of another passenger until the outer arms have again opened wide enough apart for a passenger to pass in between them. By this means the gate is opened or closed automatically, and each time it is opened the entrance of one passenger is indicated. The relations between the arms 2—2 and 3—3 will be a matter of experiment. The angle and the distance will be tested by practice until a satisfactory result is attained; but the size and arrangement are immaterial to the objects of our invention, the real purpose of it being to provide a means for recording every passenger who enters the car and to occupy a minimum space upon the platform which would be insufficient to accommodate a passenger.

One of the incidental effects of the device

which will be beneficial will be to prevent passengers from riding on the step of the car, because the recoil of the bars of the gate upon the admission of passengers will sweep across 5 the step. The speed with which the arms will recoil may be accurately regulated so as to avoid injury to an approaching passenger, and they may be cushioned so as to yield should they strike a person.

10 Having thus described our invention, what we claim and desire to secure by Letters Patent is:—

15 In a device for registering the persons passing through an opening, the combination of a pair of arms connected together so as to move together, located upon each side of the opening, one of them protruding across the opening and closing it, the other located at an acute angle with the first and protruding

outward in the direction of the approach to 20 the gate and at such an angle with the gate arm as to permit a person to pass it and contact with the gate arm, but which when the gate arm is pressed inward will follow the person and close the gate behind it, with means 25 for adjusting the relation of these arms, means to recoil the arms when displaced, means to check and regulate the return of the arms to their primary position, and means to record the motion of the arms.

Signed by us at Baltimore city & State of Maryland this 1st day of April 1907.

ELMER M. BEARD.
GEORGE A. BEARD.
